UNITED STATES PATENT OFFICE

100,212

DESIGN FOR A TRICYCLE

Harry H. Henry, Chicago, Ill., assignor to Battery Patents Corporation, Chicago, Ill., a corporation of Illinois

Application May 1, 1936, Serial No. 62,411

Term of patent 14 years

To all whom it may concern:

Be it known that I, Harry H. Henry, a citizen of the United States, residing at Chicago, in the county of Cook and State of Illinois, have invented a new, original, and ornamental Design for a Tricycle, of which the following is a specification, reference being had to the accompanying drawing, forming a part thereof, in which:

Figure 1 of the drawing is a side elevational view of a tricycle, showing my new design; and
Fig. 2 is a plan view thereof.

I claim:

The ornamental design for a tricycle, as shown.

HARRY H. HENRY.
